UPHOLSTERING CONSTRUCTION

Holley J. Norwood, Oakland, Calif.

Application September 22, 1942, Serial No. 459,257

2 Claims. (Cl. 5—263)

This invention relates to an upholstering construction suitable for upholstered chairs, davenport, and the like.

The provision of suitable spring support means in the seat and back of any upholstery construction has long been a problem. Various spring structures have been suggested. The mounting of these structures in the frame of the chair or davenport has also in turn presented its problem.

The present invention provides a simple, rugged unit spring construction possessing in and of itself sufficient support so that the use of the usual burlap or other fabric enclosing means heretofore employed is unnecessary. Further, since the spring construction is a unitary one, its installation is facilitated for it is handled as a unit and not as so many separate parts. The invention is also concerned with a novel mounting for a unit spring structure whereby, in a simple, economical and yet very satisfactory way, the unit spring structure can be positioned and supported in a chair or davenport.

The invention includes other objects and features of advantage, some of which, together with the foregoing, will be apparent upon a consideration of the structure disclosed in the drawing accompanying and forming a part hereof and incorporated herein to show the present preferred structure of the invention.

In the drawing, Figure 1 is a view of the bottom of the upholstering construction of the present invention.

Figure 2 is an enlarged fragmentary view of the bottom shown in the upholstering construction shown in Figure 1.

Figure 3 is a section taken along the line of 3—3 in Figure 1, while Figure 4 is a fragmentary view of the top of the spring structure employed.

In accordance with the present invention, the unit spring structure is first made up of a plurality of springs suitably joined together. In the drawing, I have shown a plurality of double conical springs 11, arranged in a side by side relationship but spaced from one another, the springs being arranged in rows with the axis of any one spring parallel to the axis of another spring. To secure the springs together as a unit and retain them, a wire frame member 12 is extended about the periphery of the outer springs and is suitably joined to peripheral portions of the springs as by metal clips 14. If desired tie springs 16 can be extended between diagonally positioned springs 11 to join them together and to provide additional resiliency.

5 The bottom of the spring unit is made up in a simple manner by crimping over sidewalls 17 of U members 18. A U member is extended along each peripheral edge of the spring unit and along each row of springs intermediate the ends of the spring structure whereby the several rows are joined together on each side thereof. By simply crimping the U member on a segment of each spring, a simple, strong, rugged and reliable fastening is assured.

10 To support a unit spring structure so provided in a simple manner in the frame of the upholstered piece, I preferably weave a plurality of strap members 21 and 21A across the bottom of each spring unit, each strap member being threaded through the spring structure, over and under the several U members. End 22 of each strap member is secured as by nails 23 to one side 24 of the frame construction indicated generally at 26 for the upholstered piece. The other end of each strap member is apertured as at 21 to receive a spring 28 which is joined to the opposite side 29 of the frame structure 26. Tie members 31 are also placed about that U member 18 adjacent to member 24 of the frame structure and are secured thereto as by nails to retain the spring unit in position in the upholstered piece.

15 The weaving of members 21 and 21A is so alternated that the end coils in each row are fully supported. For example, in Figure 1, the two extreme strap members 21 pass under bottom of outermost springs 11 (at the top of the figure) while the middle strap 21A is passed under and then over U members 18. In this manner the weaving is alternated to provide full support for the peripheral coils 11 at both sides of the structure. Inasmuch as the seat and back structures of the davenport and chairs and the like are substantially of the same size, relatively few sizes of unit spring structures suffice. In accordance with invention, the unit spring structure can be readily mounted in the frame of the upholstered piece and, when so mounted, are positioned to resist to a very satisfactory extent the wear and tear to which such pieces are ordinarily subjected.

20 This application is a continuation in part of my application Serial No. 412,454 filed September 26, 1941.

25 I claim:

26 1. In an upholstering construction, a peripheral frame; a spring unit comprising a plurality of separate springs arranged in rows in a substantially side by side but spaced relationship to

one another with the axis of any one spring substantially parallel to that of any other spring, means joining said springs together at both ends thereof and including means for joining together the bottom of each row of springs; said joining means including a first member joined to the bottom of each spring along one side of each row thereof, a second member joined to the bottom of each spring along a side opposite to said one side in each row; and means for positioning and securing said spring unit in said frame and including a plurality of strap members extended between opposite sides of said peripheral frame and woven through said first members and said second members, each strap member being alternately woven with respect to the strap immediately adjacent to it.

2. In an upholstering construction, a peripheral frame; a spring unit comprising a plurality of separate springs arranged in rows in a substantially side by side but spaced relationship

to one another with the axis of any one spring substantially parallel to that of any other spring, means joining said springs together at both ends thereof and including means for joining together the bottom of each row of springs; said joining means including a first member joined to the bottom of each spring along one side of each row thereof, a second member joined to the bottom of each spring along a side opposite to said one side in each row; means for positioning and securing said spring unit in said frame and including a plurality of strap members extended between opposite sides of said peripheral frame and woven through said first members and said second members, each strap member being alternately woven with respect to the strap immediately adjacent to it; means securing an end of each strap member to said frame, and a spring for joining the other end of each strap member to said frame.

HOLLEY J. NORWOOD.
